UNITED STATES PATENT OFFICE.

OTTO FELIX FEIX, OF WEST HOBOKEN, NEW JERSEY.

ABRADING-ROLL FOR LEATHER-DRESSING MACHINES.

1,202,693.

Specification of Letters Patent. Patented Oct. 24, 1916.

Application filed December 8, 1915. Serial No. 65,800.

To all whom it may concern:

Be it known that I, Otto F. FEIX, a citizen of the United States, residing at West Hoboken, in the county of Hudson and State 5 of New Jersey, have invented a new and useful Abrading-Roll for Leather-Dressing Machines, of which the following is a specification.

This invention has reference to abrading 10 rolls for leather dressing machines, and its object is to provide an abrading roll for the purpose which may be readily restored to active condition when dull, and which is free from certain objections to rolls for a 15 like purpose as heretofore used.

In leather dressing machines such as shown in Patent No. 636,970, granted to me on November 14, 1899, it has been customary to provide an abrading cylinder with a cov- 20 ering of paper carrying abrading material held thereto by glue.

In the practical operation of the machine it has heretofore been necessary, when the abrading surface is dull, to take the hardened glue and emery from the paper wheel while the wheel is in full rotation, then stop the machine, spread hot glue over the surface of the wheel and then apply emery to it, necessitating a further wait until the glue 30 with the adherent emery is perfectly dry. This is, of course, a time consuming procedure.

With the present invention an abrading roll or drum is made of carborundum or other suitable material of like nature, carborundum being preferred, the drum consisting of a cylindrical base or carrier with carborundum cylinders mounted thereon. Such an abrading device has the advantage 40 of always being in condition, for should the surface become filled with particles of flesh from the hides being treated, all that is necessary is to brush the surface off with warm water and occasionally to true up the 45 cylinder with a suitable dresser, such work requiring at the most but a few minutes.

The invention will be best understood from a consideration of the following detailed description, taken in connection with 50 the accompanying drawings forming part of this specification, with the further understanding that while the drawings show a practical form of the invention the latter is not confined to any strict conformity with 55 the showing of the drawings, but may be changed and modified so long as such

changes and modifications come within the scope of the appended claims.

In the drawings:—Figure 1 is a plan view of an abrading roll or drum constructed in accordance with the present invention. Fig. 2 is a longitudinal diametric section thereof. Fig. 3 is a cross-section of the drum. Fig. 4 is a section similar to Fig. 2, but showing a somewhat different construction 65 of supporting core or carrier.

Referring to the drawings there is shown a shaft 1, such as is employed in a leather dressing machine of the character described in the aforesaid patent. Mounted on the 70 shaft 1 is a series of broad faced pulleys 2 coacting to form a cylindrical carrier for abrading means. In Fig. 2 the carrier is made up of a series of such pulleys, while in Fig. 4 a single cylinder 2^a, instead of a 75 series of pulleys, is employed.

Mounted on the carrier 2 or 2^a are cylinders 3, 4, respectively, of suitable thickness of wall and formed of carborundum or other similar abrading material, carborundum being preferred. The end cylinders 3 each have one end 5 practically radial to the axis of rotation and provided with a circumferential groove 6 entered by an annular flange 7 on the peripheral portion of 85 a head 8. The other edge of each cylinder 3 is beveled as shown at 9, so that such edge is in a plane cutting the axis of rotation at an angle of a few degrees, say, five or ten 90 degrees, since any particular inclination is not material. The cylinder 4 has both ends beveled similarly to the ends 9 of the cylinders 3. If the drum be short, but two cylinders 3 need be employed. If the drum be longer then an additional cylinder 4 is used. 95 In the particular showing of the drawings the drum may be assumed to be twelve inches thick and forty inches long between the heads 8, the latter being held together by through bolts 10, which serve to clamp 100 the abrading sections of the drum firmly together, since it will be understood that the carrier for the abrading cylinders is made fast to the shaft 1 so as to rotate therewith.

In practice the carborundum cylinders 3 and 4 are made thick enough to withstand a speed of rotation of 900 or more revolutions per minute, and to admit of successive dressings.

The meeting ends of the cylinders are beveled to be in a plane cutting the axis of rotation at a small angle, so that the skin be-

ing treated is not engaged at the joints between the cylinders in a continuous line, since such a treatment is liable to produce markings upon the skin.

The diameter of the heads 8 is considerably less than the diameter of the abrading cylinders 3 and 4, so that they do not reach to the outer surface of the abrading roll or drum, wherefore the abrading drum is of 10 long life and may be subjected to the action of a dressing tool from time to time. The heads may be so related to the thickness of the cylinders of abrading material that the latter may be dressed down to about the 15 diameter of the heads and still be strong enough to admit of a speed of rotation as high as 900 revolutions per minute. The abrading drum is of even diameter throughout, but may be as long or as thick as may 20 be desired.

The relatively thick shells of practically solid carborundum as compared with sandpaper or surfaces of emery or other abrading material in powdered form glued to a 25 carrier, have the advantage over such glued powdered material in that the surface of the carborundum drum does not become overcharged with fatty material removed from the fleshy side of the skins or heads and may 30 be cleansed from time to time by the use of warm water.

A very fine velvet-like face may be produced on the fleshy part of the skin to be abraded by brushing a mixture of albumen, 35 water and pumice stone on the fleshy face of the skin and then rolling it up and allowing it to season before subjecting it to the action of the abrading drum. If the skins are tanned too rich, that is, if they are greasy, 40 the powdered pumice stone is spread on the fleshy side of the skin without using the mixture of water with albumen.

What is claimed is:—

1. An abrading roll for leather dressing 45 machines, comprising a cylindrical carrier adapted to be mounted on a shaft, a series of shells of abrasive material strung on the

cylindrical carrier, and means for clamping the shells in end abutment.

2. An abrading roll for leather dressing 50 machines comprising a cylindrical carrier adapted to be mounted on a shaft, a series of shells of abrasive material strung on the cylindrical carrier, heads engaging the terminal ends of the series of shells for holding 55 them on the carrier in end abutment, and bolts traversing the heads and the cylindrical carrier for holding the heads in the clamping position.

3. An abrading roll for leather dressing 60 machines comprising a cylindrical carrier adapted to be mounted on a shaft and consisting of a series of cylindrical members in end abutment, a series of cylindrical shells of abrasive material mounted on the cylindrical carrier in end abutment, heads engaging the terminal ends of the series of shells and the terminal ends of the series of cylindrical carrier members, and bolts traversing 65 the heads and the carrier for clamping 70 the shells and carrier elements together.

4. An abrading roll for leather dressing machines, comprising a supporting core, a series of abutting shells of abrasive material mounted on the core with the abutting ends 75 correspondingly beveled in planes cutting the axis of the roll at an angle, said series of shells having the terminal ends in planes substantially perpendicular to the axis of the roll with said terminal ends provided 80 with annular grooves, and clamping heads with annular flanges applied to the ends of the series with the flanges entering the grooves, the heads being of less external diameter than the external diameter of the 85 shells.

In testimony, that I claim the foregoing as my own, I have hereto affixed my signature in the presence of two witnesses.

OTTO FELIX FEIX.
